UNITED STATES PATENT OFFICE.

WESLEY A. CAIN, OF MEDICINE LODGE, KANSAS.

PORTABLE AND ADJUSTABLE SUPPORT FOR HOSE-NOZZLES.

SPECIFICATION forming part of Letters Patent No. 518,986, dated May 1, 1894.

Application filed November 2, 1893. Serial No. 489,891. (No model.)

To all whom it may concern:

Be it known that I, WESLEY A. CAIN, a citizen of the United States of America, residing at Medicine Lodge, in the county of Barbour 5 and State of Kansas, have invented a new and useful Support for Hose-Nozzles, of which the following is a specification.

The object of my invention is to provide a simple, cheap, and durable article of manufacture adapted to be placed in the ground at any place desired to support a hose nozzle at various angles and in various vertical planes, at the pleasure of the operator.

My invention consists in the device constructed and adapted to be operated as hereinafter set forth, pointed out in my claims and illustrated in the accompanying drawings, in which—

Figure 1 shows a rod or wire having three lateral bends adapted to admit a hose or nozzle. Fig. 2 is a perspective view of the complete device. Fig. 3 is a top view of the same, and dotted lines therein indicate how the hose may be turned in different directions 25 without detaching it from the support. Fig. 4 is a perspective view.

Referring to the accompanying drawings, the reference letter A designates the upright portion of the holder made complete from a single metal rod or wire with the lower end 30 preferably sharpened to be readily pressed into the ground.

Nos. 1, 2, and 3, are loops formed at suitable distances apart and adapted in size and shape and inclination and position to admit and retain a hose or hose nozzle therein. Preferably these lateral bends or loops are inclined relative to the rod or wire. That portion of the device above the loop No. 1 is bent 40 into triangular or arched shape in such a manner that the length containing the loops Nos. 1 and 2 will be in a pendent position and the open loops adapted to admit and retain a hose nozzle at different angles relative to the loop No. 1 as required to distribute water over areas of different extent without moving the device. It is obvious that any number of these loops may be used without departing 45 from the spirit of my invention.

B designates a hose and B² a nozzle thereon 50 of the ordinary kind.

In practical use the pointed lower end of the device is pressed into the ground, the hose passed through the loop No. 1 and the nozzle placed in either of the loops No. 2 and 55 No. 3 at pleasure to direct water at different angles of elevation. To change the incline of the stream and to throw water in different directions the nozzle is moved from one of said loops to the other, and to adjust the nozzle horizontally the support and hose and nozzle are jointly moved by simply turning the support upon its pivotal location in the ground.

It is obvious that the simple, cheap, strong, and durable, portable and adjustable device 65 thus constructed, from a single piece of wire or metal rod, by means of suitable tools or machinery, can be advantageously used for directing and distributing water in gardens and in lawns and much of the time and labor and 70 annoyances incident to the operation of a hose and nozzle avoided.

What I claim as new, and desire to secure by Letters Patent of the United States therefor, is—

1. As a new article of manufacture, a hose and nozzle supporter comprising a single piece of wire or metal rod, having the one end adapted to be placed in the ground, a loop near its upper portion adapted to admit and 80 retain a hose and its top portion arched and two or more loops and the pendant of the arch adapted to admit and retain a nozzle as shown and described and to operate in the manner set forth for the purposes stated. 85

2. An improved hose supporter formed of a single piece of wire or metal rod having its lower end adapted to be pressed into the ground and having the loops No. 1, No. 2, and No. 3 formed in its upper end portion and the upper end portion arched, substantially in the manner shown and described, for the purposes stated.

WESLEY A. CAIN.
